US00D980250S

(12) **United States Design Patent** (10) **Patent No.:** **US D980,250 S**
Norman (45) **Date of Patent:** **** Mar. 7, 2023**

(54) **DISPLAY SCREEN OR PORTION THEREOF
WITH GRAPHICAL USER INTERFACE**

(71) Applicant: **Google LLC**, Mountain View, CA (US)

(72) Inventor: **Christopher Norman**, Brooklyn, NY (US)

(73) Assignee: **GOOGLE LLC**, Mountain View, CA (US)

(**) Term: **15 Years**

(21) Appl. No.: **29/780,102**

(22) Filed: **Apr. 22, 2021**
